(57) **CLAIM**

The ornamental design for a steam based cleaning device as shown and described.

DESCRIPTION

The patent or application file contains at least one drawing executed in color. Copies of this patent or patent application publication with color drawing(s) will be provided by the Office upon request and payment of the necessary fee.

1. Steam based cleaning device

2. Steam based cleaning device

1.1 : Perspective

1.2 : Front

1.3 : Back

1.4 : Left

1.5 : Right

1.6 : Top

1.7 : Bottom

2.1 : Perspective

2.2 : Front

2.3 : Back

2.4 : Left

2.5 : Right

2.6 : Top

2.7 : Bottom

The designs show a stool-like design of a steam based cleaning device. The details indicated by coloring in the Reproductions form no part of the claimed design.
